CLAIM

The ornamental design for a bottle, substantially shown and described.

DESCRIPTION

FIG. 1 is a front perspective view of a bottle showing my new design;

FIG. 2 is a front elevational view, the rear being similar but plain and unornamented; and

FIG. 3 is a side elevational view, the opposite side being the same in appearance.

The drawing is shaded to show contrasting color.

FIG. 1

FIG. 3
